SHUTTLE CAR

Chester E. Andershock, Chicago, Ill., assignor to
Goodman Manufacturing Company, Chicago,
Ill., a corporation of Illinois

Application November 13, 1943, Serial No. 510,095

12 Claims. (Cl. 214—83)

This invention relates to improvements in shuttle cars adapted to transport coal or other materials from the working places of mines underground.

The principal objects of my invention are to provide a shuttle car having a movable end gate of a novel and simplified construction, cooperating with and driven along the car by the conveyer for the car as the loading operation progresses, and positively opened by the conveyer during the discharge operation.

The device of my present invention is somewhat similar to that shown and described in an application, Serial No. 504,357, filed by William R. Beck on September 30, 1943, now Patent No. 2,370,441, dated February 27, 1945, but differs therefrom in that the end gate has interengaging connection with the conveyer on the bottom of the car and is moved along the car by this conveyer as the loading operation progresses, and also is positively opened by the conveyer as the conveyer discharges its load from the car.

Other objects of my invention will appear from time to time as the following specification proceeds and with reference to the accompanying drawings wherein:

Figure 1 is a view in side elevation of a shuttle car constructed in accordance with my invention;

Figure 2 is an enlarged fragmentary view in side elevation of the discharge end of the car, with certain parts broken away and certain other parts shown in longitudinal section, in order to more clearly illustrate certain details of construction of my invention;

Figure 3 is a fragmentary view in side elevation of the discharge end of the car, drawn to the same scale as Figure 2 and showing the end gate in a different position than in Figure 2;

Figure 4 is an end view of the car with certain parts broken away and certain other parts shown in transverse section, in order to more clearly show certain details of the movable end gate; and

Figure 5 is an enlarged fragmentary isometric view of the movable end gate, with certain parts broken away so as to more clearly illustrate the details thereof.

Referring now to the details of the embodiment of my invention illustrated in the drawings, a coal haulage vehicle or shuttle car is indicated generally at 10. Said vehicle consists of an elongated material carrying body 11 including a pair of vertically disposed laterally spaced side walls 12, 12 extending the full length of the vehicle and forming the side walls of a coal carrying compartment of the car. Said side walls are flared out-

wardly at the receiving end of the car (not shown), to provide a widened material receiving hopper, to facilitate loading by the boom of a loading machine which may be extended into said hopper between said side walls. The bottom of the material carrying compartment of the car is defined by a conveyer indicated generally by reference character 15.

The material carrying body 11 is supported on two rubber-tired drive wheels 16, 16 near the rear end of the car and two rubber-tired steering wheels 17, 17 near the front end of the car. Steering is effected by a steering wheel 18 in an operator's compartment 19 near the front end of the car to one side of the conveyer.

The conveyer 15 extends for substantially the full length of the vehicle to facilitate loading of the vehicle from one end thereof and to mechanically unload the vehicle from the opposite end thereof. Said conveyer is herein shown as being an endless flight conveyer including a plurality of parallel spaced endless chains 20, 20 having a plurality of parallel spaced flights 21, 21 carried therebetween. Said endless chains and flights extend from idlers 23, 23 near the receiving end of the car along a bottom plate 24, connected between the side walls 12, 12 and forming a bottom for the conveyer, to and around drive sprockets 25, 25 on a transverse shaft 26 at the discharge end of the car. From thence said chains and flights extend along the upper side of a bottom plate 27 forming a bottom for the body of the car, to and around the idlers 23, 23.

The drive shaft 26 and conveyer 15 are suitably driven by an electric motor 28, herein shown as being mounted on the outer side of the right-hand side wall 12 of the vehicle. Said drive motor is suitably connected to said drive shaft through a worm and worm gear reduction in a casing indicated generally at 30, and a chain and sprocket drive 31, driven by the worm gear of said worm and worm gear reduction.

Referring now in particular to certain of the novel features of my invention, a movable end gate 33 is mounted between the side walls 12, 12 of the car, for movement therealong from an intermediate part of the car to the discharge end thereof, during the loading operation. Said end gate serves to hold material piled thereagainst to the tops of the side walls of the car and to advance this material towards the receiving end of the car as the loading operation progresses, so the car may be fully loaded to its discharge end by the loading boom of a loading machine extending into the receiving end of the car. It also

serves to prevent material from spilling from the car during travel of the car to its discharge station.

The movable end gate 33, as herein shown, includes a front plate member 34 suitably reinforced by vertically extending ribs 35, 35 and a stiffening strip 36, extending along the upper side thereof. Side plates 37, 37 extend rearwardly from opposite sides of said plate member. The upper margins of said side plates are disposed above the top of said plate member, to permit said front plate member to be advanced beyond the discharge end of the conveyer, during the discharging operation, as will hereinafter be more clearly described as this specification proceeds. Each of said side plates is herein shown as being reinforced by a bar 39 secured to the inner side of said side plate, as by welding, and extending along the upper side thereof, above the top of said plate member 34.

The end gate 33 and side plates 37, 37 are guided adjacent their upper ends in channelled guides 40, 40. Said guides slidably engage the upper sides of said side plates and bars 39, 39 and serve to guide and hold said end gate in a closed position. Said guides are formed by angles 41, 41 secured to the upper edges of the side walls 12, 12 and extending inwardly therefrom, the outer legs of which angles slidably engage the inner sides of said bars.

The rear portions of the side frame members 37, 37 are of an arcuate formation and serve as rockers 43, 43, when said end gate is pivoted to an open position. Gear segments 44, 44 are secured to the lower ends of said rockers, and depend therefrom and mesh with the endless chains 28, 29 of the conveyer 15. Said conveyer chains and the side plates 37, 37 engaging the channelled guides 40, 40, thus serve to hold said end gate in a closed position and move said end gate along the vehicle body. A bearing shoe 45 is secured to the lower forward portion of each side plate 37 adjacent the plate member 34 and forwardly of the gear segment 44. Said bearing shoes are adapted to rest on the upper surfaces of the endless chains 28, 29, and form a support for said end gate on said chains.

A slotted guide 47, open towards the front of said movable end gate, is provided in each side plate 37 and bar 39, above the top of the plate member 34. Said slotted guides extend longitudinally along said side plates for a portion of the length thereof and their rear ends terminate into arcuate end walls 48, 48. Each of said guides is adapted to slidably engage a pin 49, secured to and extending inwardly from a side wall 12 adjacent the discharge end of the car during movement of said end gate to an open position, to support said end gate for movement beyond the discharge end of the car, until said pin comes into engagement with the end wall 48 of said guide. At this time all but the rear portions of said end plates will be out of engagement with the guides 40, 40, and said pins will form a pivotal reaction means for said movable end gate, so that when said end walls are engaged with said pins by movement of the conveyer chains 28, 29 towards the discharge end of the car, said conveyer chains will pivot said end gate in an upward direction about said pins, as shown by broken lines in Figure 3, to open said end gate.

During operation of the machine the movable end gate 33 may first be moved to an intermediate position with respect to the length of the car, into engagement with stops 51, 51 at the rear end of the channelled guides 40, 40 (see Fig-

ure 1). This is effected by moving the conveyer towards the rear of the car. The receiving end of the car may then be fully loaded to the tops of the side walls of the car up to said end gate by the loading boom of a loading machine, and the material in the car loaded to the tops of said side walls may be advanced with said end gate by moving the conveyer towards the discharge end of the car, step by step. When said end gate has reached the discharge end of the car, the conveyer 15 is stopped and the car is ready to travel to its discharge station, the guides 40, 40 engaging the side plates 37, 37 and the gear segments 44, 44 meshing with said conveyer chains, holding said end gate in a closed position.

During the discharge operation, the conveyer is started in a direction to discharge material from the discharge end thereof. This will move the end gate beyond the discharge end of the car and will move the forward portions of said side plates out of engagement with the guides 40, 40. It will also engage the pins 49, 49 with the arcuate rear end walls of the slotted guides 47, 47 (see Figure 3), and permit the discharge of fine material and small lumps from the discharge end of the conveyer. Further movement of the conveyer will cause the gear segments 44, 44, meshing with the conveyer chains 28, 29, to pivot said end gate in an upward direction about the axis of the pins 49, 49 until the teeth of the gear segments 44, 44 are out of mesh with said conveyer chains. This will fully open said end gate, to permit material to be discharged from the discharge end of the car, the traveling conveyer and material discharging from the discharge end of the car holding said end gate in an open position until the car has been fully unloaded. When the car has been fully unloaded and the conveyer is stopped, the end gate will drop to the closed position shown in Figure 3. The conveyer may then be moved in a reverse direction towards the receiving end of the car, to return said end gate to an intermediate position with respect to the car, in position for another loading cycle.

While I have herein shown and described one form in which my invention may be embodied, it will be understood that the construction thereof and the arrangement of the various parts may be altered without departing from the spirit and scope thereof. Furthermore, I do not wish to construed as limiting my invention to the specific embodiment illustrated, excepting as it may be limited in the appended claims.

I claim as my invention:

1. In a vehicle for transporting loose material in mines underground, a wheel mounted material carrying body open at one end and having a pair of laterally spaced side walls forming a material carrying compartment, an endless conveyer forming a bottom for said compartment, and a movable end gate mounted between said side walls and guided for slidable movement therealong, said end gate being slidably guided adjacent its upper end between said side walls and being supported on and having interengaging connection with said conveyer at its lower end, so said conveyer will move said end gate along said body during the loading operation, so material piled up on said conveyer against said end gate to the tops of said side walls will be advanced to the discharge end of the vehicle, by advancing said conveyer to the discharge end of said vehicle, to cause said conveyer to fully

load said vehicle up to said end gate, by the discharge of material in the receiving end thereof.

2. In a vehicle for transporting loose material in mines underground, a wheel mounted material carrying body open at one end and having a pair of laterally spaced side walls forming a material carrying compartment, an endless conveyer forming a bottom for said compartment, and a movable end gate mounted between said side walls and guided for slidable movement therewith along adjacent its upper end, said end gate being supported on and having interengaging connection with said conveyer at its lower end, so said conveyer will move said end gate along said body during the loading operation, so material piled up on said conveyer against said end gate to the tops of said side walls will be advanced to the discharge end of the vehicle, by advancing said conveyer to the discharge end of said vehicle, to cause said conveyer to fully load said vehicle up to said end gate, by the discharge of material in the receiving end thereof, and by movement of said conveyer along the vehicle, and abutment means on said body adjacent the discharge end thereof, adapted to engage said end gate and form a pivotal reaction means therefor, to cause said conveyer to pivotally move said end gate upwardly about said abutment means to an open position through said inter-engaging connection, for discharging material from the end of said vehicle.

3. In a vehicle for transporting loose material in mines underground, a wheel mounted material carrying body open at one end and having a pair of laterally spaced side walls forming a material carrying compartment, an endless conveyer forming a bottom for said compartment, and a movable end gate for said compartment, guided adjacent its upper end for movement therewith from an intermediate position on said compartment to the discharge end thereof during the loading operation, said end gate resting on and having interengaging connection with said conveyer at its lower end, and said conveyer being adapted to move said end gate along said frame between said side walls, and to hold said end gate from movement to an open position when the conveyer is stopped, and abutment means adjacent the discharge end of said body, adapted to be engaged by said end gate and form a pivotal abutment therefor, to cause said end gate to be pivoted to an open position about said abutment means, by movement of said conveyer to discharge material from its discharge end.

4. In a vehicle for transporting loose material in mines underground, a wheel mounted material carrying body open at one end and having a pair of laterally spaced side walls forming a material carrying compartment, an endless chain and flight conveyer forming a bottom for said compartment, an end gate for said compartment, said end gate being guided for slidable movement between said side walls and having a pair of spaced gear segments extending parallel to said side walls and resting on and having interengaging connection with the chains of said conveyer, so said conveyer will move said end gate rearwardly along said body, to an intermediate position with respect thereto, to place said end gate in position for the loading operation, and will advance said end gate towards the discharge end of said vehicle during the loading operation.

5. In a vehicle for transporting loose material in mines underground, a wheel mounted material carrying body open at one end and having a pair of laterally spaced side walls forming a material carrying compartment, an endless chain and flight conveyer forming a bottom for said compartment, an end gate for said compartment, said end gate including a plate member extending transversely between said side walls and having side plates extending rearwardly from opposite sides thereof along the insides of said side walls, guide means extending along the upper sides of said side walls and forming slidable guides for said side plates, and means on said side plates resting on and having interengaging connection with the chains of said conveyer, to cause said conveyer to move said end gate along said body between said side walls.

6. In a vehicle for transporting loose material in mines underground, a wheel mounted material carrying body open at one end and having a pair of laterally spaced side walls forming a material carrying compartment, an endless chain and flight conveyer forming a bottom for said compartment, an end gate for said frame, said end gate including a plate member extending transversely between said side walls and having side plates extending rearwardly from opposite sides thereof along the insides of said side walls, guide means extending along the upper sides of said side walls having guiding engagement with said side plates and forming slidable guides therefor, abutment means on said side walls adapted to engage said side plates and form a pivotal reaction means for said end gate, and means on said side plates having interengaging connection with the chains of said conveyer, so movement of said conveyer will move said end gate along the body of said vehicle into engagement with said abutment means, and further movement of said conveyer will pivotally move said end gate about said abutment means, to an open position.

7. In a vehicle for transporting loose material in mines underground, a wheel mounted material carrying body open at one end and having a pair of laterally spaced side walls forming a material carrying compartment, an endless chain and flight conveyer forming a bottom for said compartment, an end gate for said frame, said end gate including a plate member extending transversely between said side walls and having side plates extending rearwardly from opposite sides thereof along the insides of said side walls, guide means extending along the upper sides of said side walls having guiding engagement with said side plates and forming slidable guides therefor, said side plates having interengaging connection with the chains of said conveyer so said conveyer will move said end gate along said vehicle body, abutment means on said side walls, adjacent the discharge end of said vehicle, and said side plates each having a longitudinally extending slotted guide formed therein adapted to slidably engage said abutment means and guide said end gate for movement beyond the discharge end of said conveyer, and each of said guides having a closed inner portion adapted to engage said abutment means and limit forward movement of said end gate and form a pivotal reaction means for said end gate at the discharge end of said vehicle, so said conveyer chains engaging said side plates may pivotally move said end gate to an open position.

8. In a vehicle for transporting loose material in mines underground, a wheel mounted material

carrying body open at one end and having a pair of laterally spaced side walls forming a material carrying compartment, a conveyer forming a bottom for said compartment and including a pair of parallel spaced endless chains having flights carried therebetween, an end gate for said frame, said end gate including a plate member extending transversely between said side walls and having side plates extending rearwardly from opposite sides thereof along the insides of said side wall, guide means extending along said side walls and having guiding engagement with the upper sides of said side plates, to form a guide for said side plates and end gate, and to hold said end gate from moving to an open position; and said side plates being adapted to have interengaging engagement with said conveyer chains, so said conveyer chains will move said end gate along said guides between said side walls upon operation of said conveyer.

9. In a vehicle for transporting loose material in mines underground, a wheel mounted material carrying body open at one end and having a pair of laterally spaced side walls forming a material carrying compartment, a conveyer forming a bottom for said compartment and including a pair of parallel spaced endless chains having flights carried therebetween, an end gate for said frame, said end gate including a plate member extending transversely between said side walls and having side plates extending rearwardly from opposite sides thereof along the insides of said side walls, guide means extending along the upper sides of said side walls and having guiding engagement with the upper sides of said side plates, to form a guide means for said side plates and end gate, and to hold said end gate from moving to an open position, and said side plates each having a gear segment meshing with certain links of said conveyer chains, so said conveyer chains will move said end gate between said side walls upon operation of the conveyer.

10. In a vehicle for transporting loose material in mines underground, a wheel mounted material carrying body open at one end and having a pair of laterally spaced side walls forming a material carrying compartment, a conveyer forming a bottom for said compartment and including a pair of parallel spaced endless chains having flights carried therebetween, an end gate for said frame, said end gate including a front plate member extending transversely between said side walls and having side plates extending rearwardly from opposite sides thereof along the insides of said side walls, guide means having guiding engagement with the upper sides of said side plates, to form a guide for said side plates and end gate, and to hold said end gate from moving to an open position, and said side plates each having a gear segment meshing with certain links of said conveyer chains, so said conveyer chains will move said end gate between said side walls upon operation of the conveyer, and abutment means engaging said side plates and guiding said front plate member for movement beyond the discharge end of said conveyer to disengage the front portions of said plates from said guide means, and forming a pivotal reaction means for said side plates, causing said

conveyer chains to pivot said end gate upwardly about said abutment means to an open position.

11. In a vehicle for transporting loose material in mines underground, a wheel mounted material carrying body open at one end and having a pair of laterally spaced side walls forming a material carrying compartment, a conveyer forming a bottom for said compartment and including a pair of parallel spaced endless chains having flights carried therebetween, an end gate for said frame, said end gate including a front plate member extending transversely between said side walls and having side plates extending rearwardly from opposite sides thereof, along the insides of said side walls, guide means having slidable engagement with the upper sides of said side plates, said side plates each having a gear segment meshing with certain of the links of said conveyer chains, and said side plates each having a slotted guide extending longitudinally therealong from the forward end thereof, abutment means at the forward end of said body, adapted to be slidably engaged by said guides, and said slotted guides each having a closed inner portion adapted to engage said abutment means and limit forward movement of said end gate along said body and form a pivotal reaction means for said end gate at the discharge end of said body, so said conveyer chains may pivotally move said end gate about said abutment means to an open position upon operation thereof in a direction to discharge material from said vehicle.

12. In a vehicle for transporting loose material in mines underground, a wheel mounted material carrying body open at one end and having a pair of laterally spaced side walls forming a material carrying compartment, a conveyer forming a bottom for said compartment and including a pair of parallel spaced endless chains having flights carried therebetween, an end gate for said frame, said end gate including a front plate member extending transversely between said side walls and having side plates extending rearwardly from opposite sides thereof along the insides of said side walls, guide means extending along the upper sides of said side walls and having guiding engagement with the upper sides of said side plates, to form a guide for said side plates and to hold said end gate from moving to an open position, and said side plates each having a gear segment meshing with certain links of said conveyer chains, so said conveyer chains will move said end gate between said side walls upon operation thereof, abutment means adapted to limit forward movement of said end gate, and said side plates each having a slotted guide open to the forward end thereof and extending longitudinally therealong and adapted to slidably engage said abutment means, so said abutment means may support said end gate for movement beyond the discharge end of said conveyer to disengage the front portions of said side plates from said guide means, and each of said slotted guides having a closed inner portion adapted to engage said abutment means and form a pivotal reaction means for said end gate, to cause said conveyer chains to pivotally move said end gate about said abutment means to an open position.

CHESTER E. ANDERSHOCK
